ROTARY BRUSH MEANS FOR SHOE
SHINING MACHINESJames L. Jenkins, Milwaukee, Wis., assignor, by
mesne assignments, to Associated Industries,
Inc.

Application September 30, 1946, Serial No. 700,257

7 Claims. (Cl. 15—32)

1

My present invention relates generally to improvements in the art of shoe shining, and relates more particularly to improvements in the construction and operation of a machine adapted to automatically buff and/or polish shoes.

A primary object of the present invention is to provide an improved automatic shoe shining machine which is relatively simple and compact in construction and which is moreover highly efficient in operation.

A more specific object of this invention is to provide an improved shoe shining machine wherein the polishing brushes are flexibly mounted so as to receive and effectively operate on shoes of various sizes and types.

Another specific object of the invention is to provide an improved coin-actuated and motor-driven machine which is adapted to either merely buff the operator's shoes without the application of polish or to fully polish the same.

Another specific object of my present invention is to provide an improved automatic shoe shining machine wherein one set of brushes are adapted to snugly engage and polish the sides of the operator's shoe while another brush engages the toe portion of the shoe to simultaneously polish the same.

Another specific object of the present invention is to provide an improved shoe shining machine wherein a pair of rotating brushes are adapted to be constantly resiliently urged against the opposite side portions of the operator's shoe while being simultaneously moved over the surface thereof from the toe to the heel portion and vice versa, and wherein a third brush is adapted to snugly engage the upper surface of the toe portion while being simultaneously moved back and forth thereover.

Another specific object of the invention is to provide an improved shoe shining machine wherein a predetermined amount of polish is adapted to be automatically conducted to the polishing zone.

An additional specific object of my invention is to provide an improved coin-receiving shoe shining machine in which one selected series of automatic operations is initiated upon insertion of a coin of given denomination and another selected series of automatic operations is initiated upon insertion of a coin of a different denomination.

A further specific object of the present invention is to provide an improved relatively portable automatic shoe shining unit which is durable in construction and which is composed of relatively few parts, all of which are conveniently accessible for inspection or repair.

2

Still another specific object of my present invention is to provide an improved highly dependable and automatically operable machine which is adapted to effectively polish shoes in a rapid manner while requiring minimum attention, and which may moreover be manufactured and sold at moderate cost.

These and other specific objects and advantages of the present invention will be apparent from the following detailed description.

A clear conception of the several features constituting my present improvement, and of the mode of constructing and of utilizing shoe shining machines built in accordance with my invention, may be had by referring to the drawings accompanying and forming a part of this specification wherein like reference characters designate the same or similar parts in the several views.

Fig. 1 is a diagrammatic representation of a vertical longitudinal section through one compartment of a shoe shining machine embodying my improved features, showing a shoe about to be positioned for polishing;

Fig. 2 is a diagrammatic representation of a vertical transverse section through both compartments of the machine, the polish supply mechanism having been omitted for the sake of clarity;

Fig. 3 is a fragmentary front view showing one of the sets of side brushes;

Fig. 4 is a diagrammatic perspective view of the valve actuating mechanism for supplying polish to the brushes; and

Fig. 5 is another diagrammatic view of a portion of the fluid pressure actuated polish delivery system.

While the invention has been shown and described herein as being specifically embodied in a coin-actuated automatic shoe shining machine, it is not my desire or intention to unnecessarily limit the scope or utility of the improvements by virtue of such specific embodiment.

Referring to the drawings, the improved automatic shoe shining unit shown therein comprises, in general, sets of polishing brushes housed within a casing and means accessible from the exterior of the casing for presenting shoes to the brushes for cleaning and polishing; motor-driven mechanism for operating the brushes to cause simultaneous rotation and oscillation thereof; fluid pressure actuated means for delivering polish to the brushing zone; and coin-controlled means for selectively effecting actuation either of the brush operating mechanism only or of both the brush operating mechanism and the polish delivery means.

Each set of brushes preferably comprises a pair of side brushes 10 having axially-extending bristles 11 and a toe brush 12 having radially extending bristles 13, the axially-bristled brushes 10 being adapted to snugly engage the opposite sides of a shoe 14 with the radially-bristled brush 12 adapted to likewise snugly engage the toe portion of the shoe 14 when the shoe is placed on the support 15 and moved forwardly to the brushing zone on the guides 16 through the opening 18 in the casing 17. Each of the axially-bristled brushes 10 is carried by a stub shaft 19 journaled for rotation in the lower end of a supporting arm 20 hingedly connected at 21 adjacent the upper end thereof to one of the supporting elements 23 of a composite bracket 22 to permit lateral swinging movement of the brushes 10, each bracket 22 comprising integrally connected supporting members 23, 24. The brushes 10 of each set are constantly urged toward each other and toward and against the shoe 14 by the action of helical tension springs 25, each of which is attached at one end to a lug 26 of its respective arm 20 and at the opposite end to the cross brace 27 of the bracket 22. The radially-bristled brush 12 of each set is mounted on a shaft 28 journaled for rotation in the ends of a pair of substantially horizontal supporting arms 29 pivotally carried at 30 by the lower ends of the supporting element 24 of the composite bracket 22 to permit vertical swinging movement of the brush 12, and the brush 12 of each set may preferably be constantly urged downwardly toward and against the toe of the shoe 14 by the action of a helical compression spring 31 coacting with the support 24 and the brush supporting arm 20. The entire brush assemblages hereinabove described, including two sets or series of brushes for right and left shoes, are all swingably suspended from a common shaft 32 which carries each of the composite brackets 22, and the brushes are all adapted to be simultaneously oscillated relative to the shoes 14 and their supporting members 15 in a manner to be hereinafter more fully described.

To drive the sets of brushes, a motor 35 and a series of motion transmitting chains and sprockets and belts and pulleys or sheaves are provided. The motor 35 directly drives a sprocket 36 which, in turn, is connected by a chain 37 to a sprocket 38 for transmitting rotary motion thereto. Keyed to the shaft 39 of the sprocket 38 for rotation therewith is a pulley or sheave 40 adapted to drive a belt 41 and transmit rotary motion therethrough to a pulley or sheave 42 keyed to the shaft 32. Also keyed to the shaft 32 for rotation with the pulley 42 is a series of pulleys or sheaves 43, 44, each of the pulleys 43 carrying a belt 45 adapted to transmit motion to a pulley or sheave 46 keyed to the shaft 19 of one of the brushes 10 for rotation of these brushes 10 and each of the pulleys 44 similarly carrying a belt 47 adapted to transmit motion to a pulley or sheave 48 keyed to a shaft 49 which is journaled for rotation in a pair of the arms 29 adjacent the pivotal connection 30, each shaft 49 likewise having keyed to it a sprocket 50 connected by a chain 51 to a sprocket 52 keyed to the shaft 28 of each brush 12. Also keyed to the shaft 32 for rotation with the sprocket 38 is a sprocket 53 in turn connected by a chain 54 to a sprocket 55 keyed to a shaft 56. The shaft 56 also carries a crank 57 for each set of brushes, each crank 57 being connected by a rod or pitman 58 to one of the brackets 22.

It is apparent from the foregoing that during

operation of the motor 35 rotary motion is transmitted to all of the brushes 10 through the sprocket 36, chain 37, sprocket 38, shaft 39, pulley 40, belt 41, pulley 42, shaft 32, pulleys 43, belts 45, pulleys 46 and shafts 19 and rotary motion is similarly transmitted to each brush 12 through the sprocket 36, chain 37, sprocket 38, shaft 39, pulley 40, belt 41, pulley 42, shaft 32, pulleys 44, belts 47, pulleys 48, shafts 49, sprockets 50, chains 51, sprockets 52 and shaft 23. Simultaneously with the rotation of the brushes, oscillatory motion is transmitted thereto through the sprocket 36, chain 37, sprocket 38, shaft 39, sprocket 53, chain 54, sprocket 55, shaft 56, crank 57 and connecting rod 58.

In addition to operating the brushes as hereinabove described, the motor 35 drives a sheave 61 mounted on the motor shaft, motion from the sheave 61 being transmitted by a belt 62 to a sheave 63 mounted on the shaft of an air compressor 64 to drive the compressor. Air from the compressor 64 is forced through a pipe 65 to an air storage tank 66 and from the storage tank 66 through a pipe 67 leading directly to the top of a shoe polish storage receptacle or tank 68 provided with a relief valve 69. A pipe 70 leads from the lower portion of the polish receptacle 68 below the normal level of the polish to a polish control and shut-off valve 71 which is operable by a connection 72 to periodically deliver successive batches of polish into a pipe 73 leading from the valve 71. The air supply pipe 67 also communicates, through a pipe 74, with another valve 75 which is operable by another connection 76 to periodically deliver compressed air through a pipe 77. The pipe 77 communicates with the upper end of a polish ejection pipe 78 past the lower extremity of the pipe 73, and the lower portion of the pipe 78 is provided with outlet nozzles 79, 80 which are directed respectively toward the brushes 12, 10. With this assemblage, whenever air under pressure from the supply reservoir 66 is permitted to flow through the pipe 67 and the valves 71, 75 are open, a slug of polish will be delivered from the receptacle 68 and this slug will be transported by the air delivered past the valve 75 into the pipe 78, by ejector action, from whence it will be sprayed upon the brushes through the nozzles 79, 80, branches of the pipe 78 leading to each series of brushes.

The control means for effecting actuation of the operating mechanism comprises, a fixed locally-interrupted annular contact plate 83 connected in the usual manner by wiring 81 to one terminal of the motor 35 and a peripherally-toothed control wheel 84 keyed to a shaft 85 and suitably insulated from the plate 83 and connected to the other terminal of the motor 35 by wiring 82, the control wheel 84 having a laterally projecting pin 86 revolvable with the wheel in contact with the plate 83 to provide a closed circuit and effect operation of the motor. Radiating from the shaft 85 carrying the wheel 84 is a pin 87, and when this pin 87 is in vertical upwardly extending position as shown in Fig. 1, the contact pin 86 on the wheel 84 is adjacent the local interruption or gap in the plate 83 and out of contact therewith and the motor 35 is thereby rendered inoperative.

To initially angularly displace the control wheel 84 so as to carry the pin 86 across the gap and into contact with the plate 83 to start the motor 35 and operate the brushes 10, 12, a coin-receiving means is provided which comprises, a slotted cover 88 forming a guide for a

longitudinally slidable starting arm 89 having a through opening 90 therein which is alinable with the slot in the cover 88 to receive a coin of a particular denomination, the arm 89 having an upright gripping portion 91 at one end thereof and a downwardly inclined hingedly connected actuating portion 92 at the opposite end adapted to abut the pin 87 and initially angularly displace the pin 86, shaft 85 and wheel 84 upon insertion of the proper coin in the opening or slot 90 and subsequent forward movement of the arm 89 by means of the grip 91 in an obvious manner, the coin falling through the opening 90 into a coin receptacle 93 upon movement of the arm 89 a predetermined distance forward. As the pin 86 is initially carried across the gap and into contact with the plate 83 as described, the electrical circuit for the motor 35 is closed and the motor is thereby started, the brushes 10, 12 being caused to rotate and simultaneously oscillate as hereinabove described. A pawl 94 is pivotally carried by one of the elements 23 of the composite bracket 22, the free end of the pawl 94 coacting with the peripheral teeth 95 of the control wheel 84 in a manner hereinafter more fully described. To maintain the pawl 94 in contact with the teeth 95, a coil tension spring 96 attached at one end to the medial portion of the pawl 94 and at the opposite end to a lug 97 on the element 24 of the bracket 22 and a chain 98 attached to a lug 99 on the pawl 94 and to the bracket 22 are provided. As the bracket 22 and the brushes carried thereby are oscillated by the driving means, including the crank 57 and pitman 58, as hereinabove described, the pawl 94 engages the teeth 95 of the control wheel 84 to rotate the wheel 84, shaft 85 and pin 87 counterclockwise by increments in an obvious manner. As the wheel 84 approaches one complete revolution, the inclined portion 92 of the sliding member 89 is raised about its hinge 100 by the pin 87, falling to position adjacent the pin 87 as the wheel 84 reaches the position shown in Fig. 1 and comes to rest with the pin 86 in the gap of the plate 83 and out of contact therewith, thereby halting the motor 35 and operation of the brushes 10, 12.

The coin-controlled means for effecting simultaneous actuation of the brush operating mechanism and the polish delivering means comprises, a similar slotted coin-receiving cover and guide 101 for a longitudinally slidable starting arm 102 having an opening therein for receiving a coin of a different denomination, the arm 102 having an upright gripping portion substantially like the portion 91 of the arm 89 and additionally having a lug 103 formed for coaction with the shoulder 104 on the member 89 above the hinge 100 so as to slide the member or arm 89 and the actuating portion 92 thereof forwardly upon insertion of the proper coin and longitudinal forward movement of the arm 102, thereby initially angularly displacing the pin 87, shaft 85 and wheel 84 to carry the pin 86 across the gap and into contact with the plate 83 and consequently starting the motor 35 and operation of the brushes as hereinabove described. The forward portion of the arm 102 is inclined downwardly at 105 and is adapted to coact with one arm of a bell crank 106, as shown in Fig. 4, upon forward movement thereof, the other arm of the bell crank 106 being cooperable with the end of an axially movable shaft 107 journalled in bearings 108 to shift the shaft 107 laterally toward the side of the sprocket wheel 55 during such forward movement of the

arm 102. A crank 109 is formed at the end of the shaft 107 adjacent the wheel 55 and a lug 110, cooperable with the crank 109, is provided on the side of the wheel 55 so that when the wheel 55 is driven by the motor and the shaft 107 is shifted as aforesaid with the crank 109 substantially against the side of the wheel 55, the lug 110 will contact the crank 109 and rock the shaft 107 clockwise. An arm 111 is rigidly attached at one end thereof to the shaft 107 for rocking movement therewith, the swinging end of the arm 111 carrying a rod 112 rigidly connected to the arms 72, 76 respectively associated with actuating mechanism 115, 116 for operating the valves 71, 75 respectively. From Fig. 4, it will be noted that the arm 72 merely engages a peripheral notch 117 in the actuating member or plate 115 of the valve 71 which is constantly urged to closing position by a spring 118, whereas the rod or arm 76 is pivotally connected to the actuating lever 116 of the valve 75. Such assemblage permits only momentary opening of the valve 71 by movement of the arm 72 to the right as viewed in the drawings, the end of the arm 72 becoming disengaged from the notch 117 during such movement and the spring instantly returning the valve actuating plate 115 to closed position. This momentary opening of the valve 71 however permits a slug or batch of polish to pass to the pipe 73 from the receptacle 68 and this polish is then delivered, as hereinabove set forth, by ejector action of the compressed air passing through the open valve 75 and pipes 77, 78, the valve 75 remaining open until automatically closed as hereinafter set forth. Also radiating from and rigidly attached to the shaft 107 is a trip lever 119 adapted to be rocked clockwise with the shaft 107 to engage a latch 120 simultaneously with the opening of the valves 71, 75 as aforesaid, the latch 120 thus holding the lever 119, the shaft 107 and the arm 111 in tripped and latched position. Another arm 121, radiating from and rigidly carried by the shaft 107, is attached at its free end to a coil tension spring 122 which constantly urges the shaft 107 and parts carried thereby counterclockwise and the latch 120 is similarly urged counterclockwise and against the trip lever 119 by a coil tension spring 123 coacting with an arm thereof, thereby assuring retention of the trip lever 119 in tripped and latched position. The latch 120 is positioned adjacent the side of control wheel 84 which has a laterally extending lug 124; and as the wheel 84 is rotated by increments in a counterclockwise direction by the action of the pawl 94 with the peripheral teeth 95, the lug 124 is moved toward an arm of the pivotally mounted latch 120 causing release of the lever 119 from the latch 120 as the lug 124 contacts the latch arm. As the trip lever 119 is disengaged from the latch 120, the spring 122 causes the shaft 107 and the elements carried thereby, including the arm 111, to rock counterclockwise back to the position shown in Fig. 4, thereby closing the air valve 75 through the connections 112, 76, and 116. The lug 124 is preferably so located that the valve 75 is permitted to remain open for only a relatively short time, sufficient to deliver the polish in the pipe 75 to the brushing zones through the pipe 78. To prevent backward rotation of the wheel 84 during all of the operations hereinabove described, a pivotally mounted latch pawl 125 is provided, the latch 125 having one arm thereof engaging the teeth 95 and constantly urged into

engagement therewith by a coil tension spring 126 coacting with the other arm thereof.

While the operation of the improved unit is believed apparent from the foregoing detailed description, the operation may be briefly summarized as follows: The operator may first preferably be seated on a seat provided on the support 127 with his or her shoes 14 resting on the shoe supports 15 which are then slid through openings 18 forward on the guide rails 16 to a position between the brushes 10 and with the toes of the shoes adjacent the brush 12. If it is desired to merely buff the shoes without application of polish, the proper coin is next inserted in the slot 90 and the operator may then slide the actuator 89, 92 forwardly by grasping the upright portion 91. This operation initially angularly displaces the pin 87 and the wheel 84, thereby effecting contact of the pin 86 with the plate 83 and starting the motor 35. As the motor continues to operate, motion from its shaft is transmitted by sprocket 36, chain 37, pulley 40, belt 41, pulley 42, shaft 32, pulleys 43, belts 45, and pulleys 46 to the shafts 19 of the brushes 10, causing these brushes to rotate with the axial bristles thereof constantly urged against the opposite sides of the shoes 14 by means of the hinged and laterally-swingable arms 20 and cooperable coil tension springs 25. At the same time motion from the motor shaft is transmitted by sprocket 36, chain 37, pulley 40, belt 41, pulley 42, shaft 32, pulleys 44, belts 47, pulleys 48, shafts 49, sprockets 50, chains 51, and sprockets 52 to the shafts 28 of the brushes 12, causing these brushes to likewise rotate with the radial bristles thereof constantly urged against the toes of the shoes 14 by means of the swingable arms 29 and cooperable coil compression springs 31. Simultaneously, the sprocket 53 on the shaft 39 drives the chain 54 and the sprocket wheel 55, causing the shaft 56 and crank 57 to rotate and thereby effecting oscillation of the brushes 10, 12 through the connection of the pitman 58 with the crank 57 and composite brackets 22. While the shoes 14 are thus thoroughly brushed by the rotating and simultaneously oscillating brushes 10, 12, the oscillatory movement of the brackets 22 cause the pawl 94 to rotate the wheel 84 by increments through engagement with the peripheral teeth 95 until the wheel 84 has made a complete turn and the contact pin 86 reaches the gap in the plate 83, at which time the switch is opened and further operation of the motor and brushes ceases.

If it is desired to receive a complete shine from the machine, including the application of polish, the proper coin must first be inserted in the slot provided in the member 102 and the actuating member 102 then slid forward as described with reference to the actuator 89. As the actuator 102 is moved forwardly, the lug 103 engages the shoulder 104 on the member 89 and pushes the member 89, 92 therealong, thus angularly displacing the pin 87 and starting the motor 35 and series of operations hereinabove described. In addition, the portion 105 of the actuator engages an arm of the bell crank 106, causing the bell crank 106 to shift the shaft 107 toward the wheel 55. As the wheel 55 rotates the lug 110 thereof contacts the end of the crank 109, causing the shaft 107 to rock clockwise with the trip lever 119 thereby engaging the latch 120 which holds the lever 119 and shaft 107 in tripped and latched position. As the shaft 107 is angularly displaced or rocked as above set forth, the arm 111 is also rocked, thereby moving the rod 112 and its actuator

ing connections 72, 76 to the right and rotating the plates 115, 116 for actuating the valves 71, 15 respectively to valve opening position, the valve 71 opening only momentarily, due to the coaction 5 of the arm 72 with the notch 117 of the plate 115 and simultaneous action of the spring 118, to permit a slug of polish from the receptacle 68 to enter the pipe 73 and the valve 75 remaining open, due to the pivotal connection of the arm 76 with the plate 116, a sufficient length of time to empty the pipe 73 of polish by ejector action of the compressed air passing through the pipes 77, 78. During this valve actuating operation, the motor 35 is driving the compressor 64 through the 10 sheave 61, belt 62, and sheave 63 and compressed air is being delivered through the pipe 65, tank 66 and pipe 67 to the upper portion of the polish receptacle 68. Consequently as the valve 71 is 15 opened momentarily as aforesaid, a slug of polish from the receptacle 68 is forced into the pipe 73 by air pressure in the receptacle; and as the valve 75 is maintained open, air under pressure delivered by the pipe 67 and thence through the pipe 74, valve 75, and pipes 77, 78 draws the 20 polish from the pipe 73 and delivers the same to the brushes 10, 12 through the nozzles 79, 80. As the wheel 84 rotates as above-described, the lug 124 contacts an arm of the latch 120, pivoting the latch and disengaging the trip lever 119, the 25 spring 122 then returning the shaft 107 and arm 111 to its original position and causing closing of the valve 75. Although the polish delivering means is thus rendered ineffective, the brushes, 10, 12 continue to operate on the shoes 14, being 30 driven by the motor 35 until the wheel 84 has been caused, by the coaction of the pawl 94 with the teeth 95, to complete a revolution and carry 35 the contact pin 86 to the gap in the plate 83.

From the foregoing detailed description of the 40 construction and operation of my automatic shoe shining unit it is apparent that my invention provides an improved coin actuated, motor driven machine which is adapted to effectively buff and/or polish shoes of any size. The improved 45 machine is relatively simple and compact in construction and the polishing brushes are flexibly mounted so as to receive and snugly contact either men's, women's or children's shoes. The improved mechanism has proven highly successful 50 in actual use and the unitary construction of the machine permits the same to be transported and installed in limited spaces. As is apparent from the foregoing detailed description, the machine is adapted to selectively perform two series of operations, one of which is a buffing operation only, 55 without application of polish, and the other of which is a combined buffing and polishing operation. With the improved mechanism, the motor is adapted to drive operating mechanism for the brushes as well as the compressor for delivering polish by fluid pressure means to the brushing zone. The rotating side brushes are all adapted 60 to be constantly resiliently urged toward the opposite side portions of the shoes, and the toe brushes are adapted to be urged toward the toes 65 of the shoes, and these brushes are all moved over the entire surface of the shoe by the oscillatory motion hereinabove described. The various parts of the machine may be so arranged as to operate 70 for a given period of time and with a predetermined amount of polish adapted to be automatically conducted to the polishing zone during the full polishing operation. One of the selected series of automatic operations may obviously be 75 initiated upon insertion of a coin of given denom-

ination, for example, a nickel, and the other series of automatic operations may be initiated upon insertion of a coin of a different denomination, for example, a dime. The improved machine is durable in construction and all of the parts have been found to require minimum attention, but if it is necessary to repair or replace any parts, the parts are all conveniently accessible.

It should be understood that it is not desired to limit this invention to the exact details of construction or precise mode of operation herein shown and described for various modifications within the scope of the appended claims may occur to persons skilled in the art to which this invention pertains.

I claim:

1. A shoe shining machine comprising, a shoe support, independent toe and side brushes, separate levers for swingably supporting said brushes from a common pivot for longitudinal movement of the brushes relative to a shoe resting on said support, means for simultaneously oscillating said levers, and means for swingably suspending said toe brush for independent swinging motion upon its carrying lever, said side brush supporting levers each comprising pivotally coacting sections for permitting independent swinging motion of said side brushes toward and away from each other and said side brushes being normally biased toward each other.

2. A shoe shining machine comprising, a shoe support, independent toe and side brushes, separate levers for swingably supporting said brushes from a common pivot for longitudinal movement of the brushes relative to a shoe resting on said support, means for simultaneously oscillating said levers, means for swingably suspending said toe brush for independent swinging motion upon its carrying lever, said side brush supporting levers each comprising pivotally coacting sections for permitting independent swinging motion of said side brushes about pivotal axes perpendicular to the axis of said common pivot and said side brushes being normally biased toward each other, and means carried by the common pivot of said carrying levers for positively driving all of said brushes.

3. A shoe shining machine comprising, a shoe support, independent toe and side brushes, separate levers for swingably supporting said brushes from a common pivot for the longitudinal movement of the brushes relative to a shoe resting on said support, means for simultaneously oscillating said levers, means for swingably suspending said toe brush for upward and downward independent swinging motion relative to its carrying lever, means for swingably suspending said side brushes for lateral independent swinging motion relative to their carrying levers, and means for constantly resiliently urging said side brushes toward each other.

4. A shoe shining machine comprising, a shoe support, independent toe and side brushes, separate levers for swingably supporting said brushes from a common pivot for the longitudinal movement of the brushes relative to a shoe resting on said support, means for simultaneously oscillating said levers, means for swingably suspending said toe brush for upward and downward independent swinging motion relative to its carrying lever, means for constantly resiliently restraining said toe brush against upward movement, means

for swingably suspending said side brushes for lateral independent swinging motion relative to their carrying levers, and means for constantly resiliently urging said side brushes toward each other.

5. A shoe shining machine comprising, a shoe support, independent toe and side brushes, separate levers for swingably supporting said brushes from a common pivot for longitudinal movement of the brushes relative to a shoe resting on said support, means for simultaneously oscillating said levers, means for swingably suspending said toe brush for independent swinging motion upon its carrying lever, means for likewise swingably suspending said side brushes for independent swinging motion relative to their carrying levers, and spring means for constantly resiliently urging each of said side brushes toward each other and toward a shoe positioned on said shoe support.

20 6. A shoe shining machine comprising, a shoe support, independent toe and side brushes, separate levers for swingably supporting said brushes from a common pivot for longitudinal movement of the brushes relative to a shoe resting on said support, means for simultaneously oscillating said levers, means for swingably suspending said toe brush for independent swinging motion upon its carrying lever, means for likewise swingably suspending said side brushes for independent swinging motion relative to their carrying levers, means for constantly resiliently urging said side brushes inwardly toward each other, and means for definitely limiting the extent of independent outward swinging motion of said side brushes.

25 7. A shoe shining machine comprising, a shoe support, a drive shaft disposed above said support, a pair of side brushes disposed on opposite sides of said support and being oscillatable along said support about the axis of said shaft, means for permitting each of said brushes to swing laterally toward and away from said support about an axis perpendicular to the axis of said shaft, said brushes being normally biased toward each other, and a toe brush disposed above said support and also being oscillatable along the support about the axis of said drive shaft.

JAMES L. JENKINS.
